US0D1084666S

(12) **United States Design Patent** (10) **Patent No.:** **US D1,084,666 S**
(45) **Date of Patent:** **** Jul. 22, 2025**

(54) **ORGANIZING GRID FOR STORAGE CASE**

(71) Applicant: **Magpul Industries Corp.**, Austin, TX (US)

(72) Inventors: **Tyler Heiges**, Fort Collins, CO (US); **William Furman O'Dell**, Evergreen, CO (US)

(73) Assignee: **Magpul Industries Corp.**, Austin, TX (US)

(**) Term: **15 Years**

(21) Appl. No.: **29/914,446**

(22) Filed: **Oct. 18, 2023**

(51) **LOC (15) Cl.** **03-01**

(52) **U.S. Cl.**

USPC **D3/319**

(58) **Field of Classification Search**

USPC D3/201, 207–212, 215, 217, 218, 228, D3/229, 245, 246, 254, 259, 273, 274, D3/287, 288, 291, 294, 303, 310, 314, D3/315, 318, 319, 328; D8/347, 348; D9/423–425, 428, 432, 456

CPC B65D 85/00; B65D 1/00; A45C 11/00; F41C 33/06

(57) **CLAIM**

The ornamental design for an organizing grid for storage case, as shown and described.

DESCRIPTION

FIG. 1 is a left, front, top perspective view of the organizing grid for storage case;

FIG. 2 is a front elevation view thereof;

FIG. 3 is a back elevation view thereof;

FIG. 4 is a left elevation view thereof;

FIG. 5 is a right elevation view thereof;

FIG. 6 is a top view thereof; and,

FIG. 7 is a bottom view thereof.

The evenly spaced broken lines and the unshaded areas within them in the figures showing portions of the organizing grid for storage case are included for the purpose of illustrating environment that do not form a part of the claimed design.

1 Claim, 7 Drawing Sheets
